Primary Examiner — Ania Aman(74) *Attorney, Agent, or Firm* — Cozen O'connor(57) **CLAIM**

The ornamental design for a transmission cooler for automotive applications, as shown and described.

DESCRIPTION

FIG. 1 is a front view of a transmission cooler for automotive applications showing our new design;

FIG. 2 is a back view thereof;

FIG. 3 is a top view thereof;

FIG. 4 is a bottom view thereof;

FIG. 5 is a left view thereof;

FIG. 6 is right view thereof;

FIG. 7 is a perspective view thereof; and,

FIG. 8 another perspective view thereof.

The broken lines in the drawing figures show portions of the transmission cooler for automotive applications which form no part of the claimed design.

The shade lines in the figures show contour and not surface ornamentation.
